NICHOLAS J. CONRAD, OF CHICAGO, ILLINOIS, ASSIGNOR TO SCHWEITZER & CONRAD, INC., OF CHICAGO, ILLINOIS, A CORPORATION OF ILLINOIS.

CUT-OUT FOR ELECTRICAL CIRCUITS.

1,233,192.

Specification of Letters Patent. Patented July 10, 1917.

Application filed October 16, 1915. Serial No. 56,177.

To all whom it may concern:

Be it known that I, NICHOLAS J. CONRAD, a citizen of the United States, residing at Chicago, in the county of Cook and State of Illinois, have invented a certain new and useful Improvement in Cut-Outs for Electrical Circuits, of which the following is a full, clear, concise, and exact description, reference being had to the accompanying drawings, forming a part of this specification.

My invention relates to cut-outs for electrical circuits. On lines employing high voltages, fuses are desirable to protect the apparatus and circuits just as much as in low voltage work. While in low and moderate voltage work and especially in small capacity circuits the fuse may be replaced while voltage is upon the line without danger to the operator, special precautions must be taken where high voltages are employed or large amounts of power are to be dealt with. In such case, especially where high voltages are employed, the fuse cannot be replaced in the line while voltage is on without great danger to the operator. In small power work it is common to insert a knife or snap switch in the circuit and when a fuse is to be replaced the switch is opened thus removing voltage from the line. In large power work the employment of switches for this purpose is prohibited by the cost of switch construction involved and also because opening of a switch does not remove all dangerous voltage from the line, especially from a long transmission line. On three phase systems opening of one line only would be impracticable. As a result the so-called fused cut-out has been developed. In general this comprises a switching block or blade removable from the line terminals, this block or blade having incorporated therein a fusible link or conductor. The block may be withdrawn completely from the line terminals in order to inspect or repair the same without subjecting the operator to danger from the line voltage. Where the fusible link comprises a soft metal conductor the construction is relatively simple, but for high voltages or for large capacity such type of fuse cannot be employed and a different form of fuse and mounting must be provided.

The cut-out which I shall describe is de-

signed to employ a particularly efficient fuse of the type disclosed in the patents to Edmund O. Schweitzer and Nicholas J. Conrad Nos. 1,050,493, 1,033,384 and 1,008,496, but it is to be understood that any other suitable fuse or link may be employed.

It is desirable that the cut-out be made as compact as possible; that the structure be completely weather-proof for outdoor installations; that the operator be suitably protected while manipulating the device and that a suitable indicator be provided for indicating from the outside the condition of the fuse.

The object of this invention is to provide a cut-out or fuse block which will embody the above and other advantages.

In the accompanying drawings in which I have illustrated an embodiment of my invention—

Figure 1 is a longitudinal vertical section of one form of fused cut-out;

Fig. 2 is an elevation of the same;

Fig. 3 is a fragmentary view of the position of the lower end of the fuse and the handle carrying the same;

Fig. 4 is a front elevational view of a modified form of the invention;

Fig. 5 is a detail view showing the top of the handle or mounting of the fuse holder;

Fig. 6 is a bottom plan view of the shell or casing shown in Figs. 1 and 2;

Fig. 7 is a fragmentary elevation of a fuse mounting block and handle for high voltages;

Fig. 8 is a cross-sectional view of a form of a device employing a resistance which is inserted in the circuit before the circuit is broken; and

Fig. 9 illustrates a connecting link without a fuse.

The fuse 1 which preferably is of the type disclosed in the above mentioned patents, comprises a glass tube 2 provided at the top with the cylindrical terminal 3 and at the bottom with a similar terminal 4 which contains a flexible conductor 5, surrounded by a coil spring 6 and a transparent arc extinguishing liquid 7. The terminals 3 and 4 are formed in the shape of ferrules which embrace the ends of the glass tube 2. I shall not describe this particular type of fuse in detail. Suffice it to say that upon

blowing of the fuse the conductor 5 is released from the top terminal 3 and the coil spring 6 immediately draws the end of the flexible conductor down into the arc extinguishing liquid thereby extinguishing or destroying the arc quickly and effectively. The top of the fuse is normally closed by a disk 56 shown in dotted line in Fig. 1, but upon "blowing" this disk may be blown off and the top opened so that the hot gases formed by blowing may escape from the open glass tube through the vent in the sleeve and out beneath the petticoat as is shown in the arrows in Fig. 1. The fuse 1 is surrounded by an insulating shell 8 which may be constructed of fiber impregnated with bakelite or the like, or any suitable weather-proof insulating material. The top of the tube 8 is provided with a cap or a hood 9 which closes off the open end of the tube, and forms a petticoat for the parts later to be described.

The upper end of the tube 8 is provided with a series of apertures 10 which open into the space 11 between the hood and the tube. The gases that are evolved upon blowing of the fuse 1 may escape through the apertures 10 and the space 11, and are thus diverted completely from the hands or the face of the operator.

A suitable sleeve 12 which comprises a metal band encircling the terminal 3 is secured upon the inside surface of the insulating tube 8 and forms a stationary line terminal.

This terminal 12 is provided with a plurality of spring fingers 13 which are arranged to make separate yielding contact with the terminal 3. The flexible lead wires 14 which are preferably stranded cables are secured at the inner end to the metallic ring 12 and at their outer end are provided with a suitable connector 15. The lower end of the insulating tube 8 is surrounded by a short sleeve 16 which is secured thereto by a water-proof joint. The lower end of the tube 8 is provided with the metal sleeve 17 which comprises a ring of metal having the spring fingers 18 extending upwardly and embracing the terminal 4 of the fuse 1. The stranded cables 19 are secured to the sleeve 17 and are connected together to the connector 20 at their outer ends. A metal sleeve 21 is mounted on the inside of the insulating sleeve 16 and is secured by pins or the like to the insulating tube 8. The fuse 1 is mounted upon a suitable mounting block 22 which is provided with a handle 23 at its lower end for introducing the fuse in place in the sleeves 12 and 17.

A short cylindrical metal block or top 24 is interposed between the terminal 4 of the fuse and the mounting block 22. The block 24 is secured to the mounting block 22 by suitable screws 29 or the like and is secured

to the terminal 4 of the fuse 1 by means of a short threaded stud 25, shown in dotted lines in Fig. 1. The metal block 24 is provided with a threaded socket for receiving the stud 25 and is provided also with a small counter-bore in which lies a spring washer 28 for locking the parts together. A suitable guard or deflector 30 is placed between the mounting block 22 and the handle 23. This deflector serves to deflect from the hands of the operator any gases that may escape down through the tube 8. It also serves to close off the bottom of the sleeve 16. The metal top 24 of the mounting block 22 is provided with a pair of oppositely disposed pins 31.

The pins 31 are adapted to coöperate with suitable slots to form what is known as a "bayonet joint" so that when the pins 31 rest in the uppermost and inner end 32 of the slots the fuse 1 will be securely held in place in the sleeve sockets 12 and 17. The sleeve 16 is provided with suitable indications 33 upon the outside thereof for indicating the position which the pins 31 must take before the fuse can be inserted. When the pins are in line with the indications 33 they will clear the metal sleeve 21, being then in register with the notches 34 that are formed in the metal sleeve 21. The notches 34 communicate with a slot 35 disposed at right angles thereto and this slot connects with a vertically disposed slot 36 which in turn communicates at its upper end with the horizontally disposed slot 32, above mentioned.

It can be seen that for the insertion of the fuse 1 and mounting block 22 into place it is necessary first that the pins 31 be brought into register with the indications 33 so that the pins may be introduced into the notches 34. The handle 23 is then given a turn to the right to bring the pins 31 through the horizontal slot 35 into the vertical slot 36. The handle is then pushed upward to bring the pins 31 along the slot 36 to the horizontal portion 32 where the handle is given a final turn to the right and the fuse, and the block are then firmly held in place.

If by chance the fuse should be inserted upon a line which is short-circuited there would be a tendency for the fuse, the mounting block and the handle to be kicked outward out of the hand of the operator. To prevent this as well as to prevent dropping of the fuse and mounting block I have provided the double bayonet joints. The pins 31 are in the vertical portion 36 of the slot when the circuit is closed between the lower terminal 4 and the socket. If the fuse blows at this time, the recoil or kick will be taken up by the pins 31 resting in the horizontal portion 35 of the slot.

I wish to call particular attention to the fact that the top of the fuse 1, from which

the gases formed by blowing of the fuse are expelled, is closed off from the bottom where the hand of the operator might be subjected to painful burning.

5 In case the operator inserts a fuse when the line is short-circuited, the blowing of the fuse will not burn his hand because the ferrule 3 will be in the sleeve 12 when the ferrule 4 enters the sleeve 17. Even if the 10 sleeve block and handle are kicked down by explosion of the fuse, the ferrule 3 and the sleeve 12 will still be in contact when the pin 31 is at the end of the slot 36.

Thus there is a gas seal between the explosion or arc chamber 50 which is formed in the top of the sleeve 8 above the fuse and the bottom of the device.

A suitable mounting bracket which preferably consists of the base 37 and the cap or 20 yoke 38 provides for mounting the cut-out upon a cross arm or the like. The main sleeve or tube 8 is provided with apertures near the top of the fuse and a pair of small transparent windows 39 are held over these 25 apertures by means of a collar or sleeve of insulation 40 so that the operator or attendant may sight through the windows 39 to ascertain the condition of the fuse 1. It is to be understood that when the fuse has 30 blown the coil spring 6 and the flexible conductor 5 will be moved downward and will no longer be visible through the windows 39 so that a clear view may be had through this window.

35 For an exposed or outdoor installation in which there is danger of the window becoming foggy from smoke, soot or the like, I provide a band or sleeve 41 which is let into the sleeve 40 and has an aperture co-operating with the opening 39 which aperture may be brought into register with the opening 39 by rotating the band 41.

For especially high voltages I employ a sleeve of insulation 42 between the co-operating parts of the mounting clamp 37, 38, as shown in Fig. 4.

For high voltage insulation, the handle 23 is protected by a petticoat 43 as shown in Fig. 4 and to secure this type of insulation, 50 I employ an insulator 44 of suitable material between the mounting block 22 and the handle 23. As shown in Fig. 7, this insulator 44 may be provided with a plurality of petticoats and may in fact consist of a 55 regular line insulator.

In Fig. 8 I have shown a modification of the fuse arrangement in that the lower terminal 4 is provided with an extension 45 of high specific resistance material which 60 surrounds the lower end of the fuse and is in direct contact with the annular terminal 4. It is to be noted in each of the forms shown that the upper terminal 3 of the fuse 1 is of a slightly less diameter than the lower terminal 4 and the contact sleeves 12 and 17

are made of corresponding sizes. The terminal 3 is also of greater axial length than the terminal 4 and when the fuse is withdrawn from its mounting the connection will first be broken between the terminal 4 and the 70 socket 17. In the form of cut-out shown in Fig. 8 the lower terminal 4 of the fuse 1 will leave its socket 17 which will then make contact with the resistance 45 before the circuit is broken and thus not only will the 75 arc which tends to be formed be lessened, but the disturbance in the circuit caused by breaking the flow of current will also be less. The resistance 45 serves as an initial and final contact to carry the arc when the 80 fuse is inserted or withdrawn.

If it is desired to omit the fuse 1, a connecting link, such as shown in Fig. 9 may be employed instead. Such a connecting link consists of a body 47 of insulating material provided with the usual terminals 3 and 4 which are connected together by a wire 48 or other suitable conductor which passes through the body 47. With the dummy fuse 46 the device operates merely 90 as a cut-out or switch for opening the circuit.

It can be seen from the above that I have provided a particularly efficient and economical cut-out or fuse block which is protected against disturbance from the elements and which is constructed to guard the operator against injury. The pins 31 and the co-operating grooves form readily releasable detent means for closing the open end 100 of the sleeve or tube 8 and for connecting and disconnecting the fuse from its sockets or terminals. The flexible conductors 14 and 19 which connect with the stationary terminals give ample current carrying capacity but at the same time form flexible leads for attachment to the circuit conductors. The employment of a number of flexible cables side by side to form a conducting lead of sufficient capacity allows of convenient attachment to the stationary terminals, and at the same time occupies the least space radially of the body of the cut-out. The fuse is inserted in two stages, the first stage when the pin is in the horizontal slot 115 35 brings the upper terminal 3 of the fuse 1 into contact with the sleeve 12 but does not cause engagement of the terminal 4 with the sleeve 17. Upon upward movement of the pins 31 in the slot 36 contact is made between the lower sleeve 4 and the socket 17 and when the pin 1 is in the slot 32, the parts are in proper position and are secured together.

While I have shown and described my invention with reference to the particular details of construction of one embodiment, it is to be understood that the invention may appear in different forms and with numerous modifications and variations such as will 125 130

suggest themselves to one skilled in the art. But I consider all such modifications and variations to be included within the spirit and scope of my invention.

5. What I claim is:

1. In combination a straight cylindrical sleeve of insulating material adapted to be placed in a vertical position, said sleeve having the walls adjacent its upper end apertured to form vents, an annular contact lying against the walls of said sleeve below said vents, a cylindrical cap of insulation secured to the top of said sleeve, said cap being undercut at said vents to form a petticoat 70 for said vents, a plurality of flexible stranded conductors lying side by side in the space between the petticoat and the sleeve and having their inner ends secured to said annular contact, an open annular contact 75 lying against the walls of said sleeve adjacent the lower end thereof, a cylindrical sleeve secured to the lower end of said first sleeve, said latter sleeve forming a petticoat about the lower end of said first sleeve, said 80 petticoat being recessed, a plurality of stranded flexible conductors lying side by side in said recess and being connected to said lower annular contact, and a cylindrical fuse having contacts which are adapted to be embraced by said annular contact, said fuse being organized to discharge the gases of the arc from the upper end thereof upon blowing, said gases being dissipated through 85 said vents in the walls of the first sleeve.
2. In combination a straight cylindrical sleeve of insulating material adapted to be placed in a vertical position, said sleeve having the walls adjacent its upper end apertured to form vents, an annular contact 90 lying against the walls of said sleeve below said vents, a cylindrical cap of insulation secured to the top of said sleeve, said cap being undercut at said vents to form a petticoat for said vents, a plurality of flexible 95 stranded conductors lying side by side in the space between the petticoat and the sleeve and having their inner ends secured to said annular contact.
3. In combination a straight cylindrical sleeve of insulating material adapted to be placed in a vertical position, said sleeve having the walls adjacent its upper end apertured to form vents, an annular contact 100 lying against the walls of said sleeve below said vents, a cylindrical cap of insulation secured to the top of said sleeve, said cap being undercut at said vents to form a petticoat for said vents, a plurality of flexible 105 stranded conductors lying side by side in the space between the petticoat and the sleeve and having their inner ends secured to said annular contact.
4. In combination a straight cylindrical sleeve of insulating material adapted to be placed in a vertical position, said sleeve having the walls adjacent its upper end apertured to form vents, an annular contact lying against the walls of said sleeve below said vents, a cylindrical cap of insulation secured to the top of said sleeve, said cap being undercut at said vents to form a petticoat 110 for said vents, a plurality of flexible stranded conductors lying side by side in the space between the petticoat and the sleeve and having their inner ends secured to said annular contact, an open annular contact lying 115 against the walls of said sleeve adjacent the lower end thereof, a cylindrical sleeve secured to the lower end of the said first sleeve, said latter sleeve forming a petticoat about the lower end of said first sleeve, said petticoat being recessed, a plurality of stranded flexible conductors lying side by side in said recess and being connected to said lower annular contact, said annular contact being adapted to embrace the contact of a cylindrical fuse.
5. In combination a cylindrical sleeve having at its upper end a vent opening freely into the atmosphere, a petticoat covering said vent, an upper stationary contact in 120 said sleeve, a lower stationary contact in said sleeve and a cylindrical fuse inserted axially into conducting relation with said stationary contacts, said fuse having a normally closed vent at one end, said vent being opened by blowing of the fuse, said fuse forming a gas seal with one of said stationary contacts below said vent to prevent the hand of the operator from being injured.
6. In combination a cylindrical sleeve, an upper stationary contact, said sleeve having an explosion or arc space above said upper contact, a lower stationary contact, said contacts being mounted on said sleeve and insulated from each other, a cylindrical fuse 125 having terminals cooperating with said contacts, said fuse having its one end adapted to be opened by blowing of the fuse, said fuse being inserted axially into circuit closing relation with said contacts, and closing off the explosion or arc space from the opening through which the fuse is inserted.
7. In combination a cylindrical sleeve, an upper stationary contact mounted in said sleeve, a lower stationary contact mounted in said sleeve, a fuse comprising a cylindrical body of insulation having upper and lower contact terminals, an arc extinguishing liquid in said body of insulation, said fuse having its lower end permanently closed 130

- and having its upper end provided with a normally closed vent, a conductor within the body of insulation joining said terminals, said fuse having means for breaking the circuit between said terminals, and simultaneously discharging the gases from the upper end thereof only, said cylindrical sleeve having a vent or vents freely opening into the atmosphere adjacent said end of the fuse. 5
8. In combination a cylindrical sleeve, an upper stationary contact mounted in said sleeve, a lower stationary contact mounted in said sleeve, a cylindrical fuse inserted axially, said fuse being in current conducting relation to said stationary contacts, said fuse having terminal contacts of different diameter and having means for discharging gases from the end having the contact of smaller diameter when the fuse blows, said sleeve having vents opening freely into the atmosphere to discharge said gases. 10
9. In combination a cylindrical sleeve, a stationary cylindrical contact mounted in said sleeve, a second stationary cylindrical contact mounted in said sleeve, said contacts being spaced apart from each other, an inclosed cylindrical fuse having cylindrical terminals coöperating with said stationary contacts, said fuse being inserted axially and closing off the upper end from the space below the first cylindrical sleeve and forming a gas seal, the upper end of said sleeve being completely closed off by said seal from said lower end, said fuse having means for opening one end thereof when the fuse blows and said sleeve having open vents directly communicating with the atmosphere at said end of the fuse. 15
10. In combination a cylindrical sleeve, an upper stationary contact mounted in said sleeve, a lower stationary contact mounted in said sleeve, a cylindrical closed fuse having terminals thereupon, said fuse being moved into conducting relation with said stationary terminals by inserting the same axially into said sleeve, said lower stationary terminal being of greater diameter than said upper terminal, said fuse having means for opening one end thereof when the fuse blows, and said sleeve having open vents directly communicating with said end of the fuse. 20
11. In combination a cylindrical sleeve, a pair of spaced open annular stationary contacts in said sleeve, said sleeve having an explosion chamber therein above said upper stationary contacts, a cylindrical fuse inserted axially in said sleeve and a part thereof lying within each of said contacts, said fuse making contact with said stationary contacts, a mounting block secured to said fuse, a handle secured to said mounting block and means within said sleeve for preventing movement of said fuse, said means comprising a bayonet slot lying wholly within said sleeve and a pin mounted on said mounting block, said pin being adapted to enter said slot. 25
12. In combination a cylindrical sleeve, a pair of spaced stationary contacts in said sleeve, a cylindrical fuse joining said contacts, a petticoat cover for the top of said sleeve and a petticoat cover for the bottom of said sleeve, and flexible connecting leads passing under said petticoats and secured conductively to said stationary contacts, said sleeve having a vent or vents communicating with the atmosphere under said upper petticoat, said fuse being adapted to blow out at one end and discharge through said vent. 30
13. In combination a cylindrical sleeve, a pair of stationary annular contacts mounted in said sleeve, said contacts being spaced apart, a cylindrical fuse fitting into and connecting said contacts, said fuse being mounted axially of said sleeve, said sleeve having an aperture or vent adjacent the upper end thereof, a cap closing the top of said sleeve, said cap having a cylindrical petticoat over said aperture, a flexible stranded conductor passing beneath said petticoat and through said aperture and connected to said upper stationary annular contact. 35
14. In combination a cylindrical sleeve, having a pair of annular contacts mounted therein and fitting within the side walls of said sleeve, said contacts being spaced apart, a cylindrical fuse fitting into and connecting said contacts, an aperture or vent adjacent the top of said sleeve, a cap for closing the top of said sleeve, said cap having a petticoat over said aperture, said sleeve having sight openings therethrough adjacent the top of said fuse, said fuse being adapted to blow out of one end thereof and to give an indication of the same. 40
15. In combination a cylindrical sleeve, having a pair of stationary annular contacts mounted therein and fitting around the inside walls of said sleeve, a cylindrical fuse fitting into and connecting said contacts, a petticoat secured to the lower end of said sleeve and having a cylindrical portion extending below the same, a flexible stranded conductor connected to said lower stationary contact and passing under said petticoat. 45
16. In combination a cylindrical sleeve having a pair of stationary open annular contacts mounted therein and fitting against the side walls of said sleeve, a cylindrical fuse connecting said contacts, said fuse being adapted to be inserted into both of said annular contacts, a mounting block secured to said fuse, an enlarged sleeve secured to the lower end of said first sleeve, said latter sleeve having a cylindri- 50

cal petticoat, said petticoat encircling said mounting block and a handle secured to said mounting block.

17. In combination a sleeve, a pair of stationary contacts in said sleeve, a fuse, said fuse having cylindrical contact portions on the ends thereof, a mounting block secured to said fuse, a handle secured to said mounting block, a metal plate having a bayonet slot, said plate lying wholly within said sleeve, and a pin on said mounting block, coöperating with said slot to hold said block and fuse within the sleeve.

18. In combination a cylindrical sleeve member, a pair of spaced stationary open annular contacts mounted on the walls of said sleeve member, a fuse having cylindrical terminal portions adapted to coöperate with said stationary contacts, a mounting block secured to said fuse, a bayonet slot in said sleeve member and a pin secured to said mounting block, said fuse being organized to discharge the gases of the arc axially from one end thereof.

25 19. In combination an external insulating supporting sleeve having a pair of open annular contacts mounted on the inner walls thereof, a cylindrical fuse member having metallic ferrules forming contacts on the ends thereof, the upper ferrules being of greater length than the lower ferrules, said fuse being organized to discharge the gases of the arc axially from the upper end thereof, means comprising a handle for inserting said fuse axially into said annular contacts and means for holding said fuse and handle against outward movement after said fuse has engaged the upper contact, and before it has engaged the lower contact, said 35 40 means comprising a double bayonet slot and a pin movable into and out of said slot.

20. In combination a cylindrical fuse member organized to discharge the gases of the arc axially from one end thereof, a cylindrical mounting block coöperating with screw threaded parts for securing said fuse member and said block in axial alinement, and a sleeve member inclosing said fuse member and said block, said block and said 45 50 sleeve having coöperating locking means for holding the parts together, said locking means comprising a double bayonet slot and a pin.

21. In combination a cylindrical sleeve member, having stationary annular contacts therein, a cylindrical fuse member having terminal portions adapted to coöperate with said stationary contacts, said fuse member being organized to discharge the gases of the 55 60 arc axially from one end thereof, a mounting block secured to said connecting member and interlocking parts on said mounting block and said sleeve member for securing said parts together, said parts comprising a

double bayonet slot and a pin movable in 65 said slot.

22. In combination a sleeve member adapted to receive a fuse, a fuse organized to discharge the gases of the arc axially from one end thereof, a mounting block for 70 supporting the fuse, a slot in said sleeve member, said slot comprising two vertical portions and two horizontal portions and a pin on said mounting block coöperating with said slot.

75 23. In combination a sleeve member having stationary annular contacts therein lying against the walls of the sleeve, said contacts being spaced apart, a fuse for connecting said contacts, said fuse being organized 80 to discharge the gases of the arc axially from one end thereof, a mounting block secured to said connecting member, said sleeve member having a slot therein and said mounting block having a coöperating pin, 85 said slot comprising two vertical and two horizontal portions.

24. In combination a cylindrical sleeve member, having stationary contacts therein, a cylindrical connecting member having 90 contact portions engaging said stationary contacts, a mounting block secured to said connecting member, said sleeve member having a petticoat surrounding said mounting block below said stationary contact, said 95 mounting block having petticoated insulating means secured thereto below said petticoat and a handle secured to said mounting block below said insulating means.

25. In combination a cylindrical sleeve 100 member having stationary contacts secured therein, a cylindrical fuse member having terminals adapted to engage said stationary contacts, resistance means connected to one of said terminals, said resistance means being adapted to engage one of said stationary contacts and to be placed in circuit in series with said fuse member when said fuse member is moved into said sleeve in position to connect the stationary contacts.

105 26. In combination a cylindrical sleeve member, an annular stationary contact member mounted adjacent the lower end thereof, a stationary contact member adjacent the upper end thereof, a cylindrical fuse means 110 115 adapted to be inserted axially and lie within said stationary contact member for connecting the same, resistance means connected to the lower end of said fuse and means for moving said fuse axially into said stationary annular contact and against said upper stationary contact whereby the lower stationary annular contact member is brought into contact with the resistance means in series with the fuse.

120 125 27. In combination a sleeve member, a stationary contact mounted in the upper end thereof, a contact member mounted in the

- lower end thereof, a cylindrical fuse member having terminals adjacent the ends thereof, said terminals connecting with said stationary contacts, resistance means connected to 5 said lower terminal, and means for bringing one end of said resistance in contact with said lower contact after the upper end of said fuse means engages said upper contact means and before the lower terminal en- 10 gages the lower stationary contact.
28. In combination a cylindrical conducting member having a metal ferrule adjacent the end thereof, said ferrule having its end faced off normal to its axis, a threaded stud 15 secured thereto, a mounting block having a threaded socket for receiving said stud, and a spring washer between said ferrule and said mounting block, said mounting block having its top surface faced off normal to its 20 axis to abut against the end of the fuse ferrule and having a circular recess for said spring washer.
29. In combination a cylindrical sleeve of 25 insulation, a pair of spaced stationary contacts in said sleeve, a fuse connecting said contacts, said fuse comprising a glass tube having metal ferrules for connecting said spaced stationary contacts, said sleeve having diametrically opposite apertures there- 30 through, said fuse having an element normally lying in line with said aperture to obstruct the passage of light therethrough and adapted to be moved out of said line upon
- blowing of the fuse and means for closing said diametrically opposite apertures. 35
30. In combination a vertical sleeve of insulation, a pair of annular contacts lying against the walls of said sleeve upon the interior thereof, said walls having diametrical apertures therethrough intermediate 40 said annular contacts, a band having apertures adapted to be brought into register with the apertures in said sleeve and a cylindrical fuse adapted to be inserted axially into said annular contacts to connect the 45 same, said fuse having a portion normally lying in line with said apertures and adapted to be removed when the fuse is blown so as to give a clear view for the transmission of light through said apertures. 50
31. In combination a cylindrical sleeve member having stationary contacts secured therein, a cylindrical fuse member having terminals adapted to engage said stationary contacts, resistance means connected to one of said terminals, said resistance means being adapted to engage one of said stationary contacts and to be placed in circuit in series with said fuse member upon moving said fuse out of said sleeve member to cause 60 the circuit to be broken at said resistance means. 55
- In witness whereof, I hereunto subscribe my name this 13th day of October, A. D. 1915.

NICHOLAS J. CONRAD.
